UNITED STATES PATENT OFFICE

90,968

DESIGN FOR A VEHICLE TIRE

Carlo Bottasso, Milan, Italy, assignor to Societa Italiana Pirelli, Milan, Italy, a corporation of Italy

Application July 7, 1933. Serial No. 48,660

Term of patent 7 years

To all whom it may concern:

Be it known that I, CARLO BOTTASSO, an Italian subject, residing at Milan, Italy, have invented a new, original, and ornamental Design for Vehicle Tires, of which the following is a specification, reference being had to the accompanying drawing, forming part thereof.

Figure 1 is a fragmentary perspective view of a tire showing my new design.

Figure 2 is a cross-sectional view of the tire shown in Fig. 1.

The design of the tread adjacent the side walls of the tire is identical on both sides.

I claim:

The ornamental design for a vehicle tire, as shown and described.

CARLO BOTTASSO.
